COMPACT SHOE SHINE KIT

Leonard G. Kernal, St. Cloud, Minn.

Application October 4, 1955, Serial No. 538,421

1 Claim. (Cl. 15—265)

This invention relates to a shoeshine kit.

The object of the invention is to provide a shoeshine kit which can be readily collapsed when it is not being used.

Another object of the invention is to provide a shoeshine kit which can be opened to provide a support for a person's foot when the shoe is being shined, and wherein a container is hingedly mounted in the stand so that the container can be used as a convenient storage base for brushes, shoe polish and the like.

A further object of the invention is to provide a shoeshine kit which is extremely simple and inexpensive to manufacture.

Other objects and advantages will be apparent during the course of the following description.

In the accompanying drawings, forming a part of this application, and in which like numerals are used to designate like parts throughout the same:

Figure 1 is a side elevational view of the shoeshine kit shown in closed or collapsed position, and with parts broken away and in section.

Figure 2 is a fragmentary side elevational view of the shoeshine kit shown in open position.

Figure 3 is a fragmentary rear elevational view of the shoeshine kit.

Figure 4 is a fragmentary top plan view of the stand.

Figure 5 is a fragmentary elevational view illustrating the locking lug.

Figure 6 is a sectional view taken on the line 6—6 of Figure 3.

Referring in detail to the drawings, the numeral 10 designates a rod which may be made of any suitable material such as metal. There is further provided a pair of legs 12 which are arranged in converging relation with respect to each other, and the legs 12 are spaced from the rod 10 so as to form a tripod-like stand. Extending from the upper end of each of the legs 12 is a first section 14, Figure 4, and each of the first sections 14 terminates in a straight portion 15. A crosspiece 16 extends between the pair of straight portions 15, and the crosspiece 16 extends through the eyelet 11. The portions 14, 15 and 16 cooperate to define a support member 13 whereby a person can place his foot on the support member 13 as when a shoe is to be conveniently shined or polished.

Secured to each of the legs 12 is a bracket 17, and a cover or lid 18 is secured to the pair of brackets 17 in any suitable manner. The cover 18 is arranged contiguous to the inner surfaces of the legs 12. A container or housing 19 is hingedly or pivotally connected to the lower end of the cover 18 by means of a hinge 20, Figure 2. The container 19 can be used to hold shoe polish, brushes, rags or the like.

There is further provided a lug 21 which is secured to the container 19 in any suitable manner, and the lug 21 is provided with a slot or cutout 22 which receives therein the rod 10.

From the foregoing, it is apparent that there has been provided a shoeshine kit and when the device is not being

2

used it can be folded or collapsed to the position shown in Figure 1. Thus, with the parts arranged as shown in Figure 1 the cover 18 snugly closes the container 19, and the container 19 may have shoe polish, brushes, rags or the like therein. The lug 21 with the slot 22 engages the upper portion of the rod 10 so as to maintain the parts in their closed position with sufficient friction to prevent accidental opening thereof. However, when the shoes are to be shined, the parts are moved from the position shown in Figure 1 to the position shown in Figure 2 so that the lug 21 moves down the rod 10 and forms a locking mechanism to hold the rod 10 separated or spaced from the legs 12. Also, in the position shown in Figure 2 the container 19 is open or in a substantially horizontal position so that access can be readily had to the interior of the container 19 as when the polish or brushes or the like are to be removed. With the parts arranged as shown in Figure 2, a person's foot can be supported on the support member 13 so that a shoe on this foot can be conveniently or readily shined or polished. The web 16 pivotally engages the eyelet 11.

The shoeshine set of the present invention is compact when in closed position so that it can be readily placed out of the way as for example it can be placed behind a door or readily positioned in a closet. In Figure 1 the device is shown in closed position and in Figure 2 the device is shown in open position. With the device arranged as shown in Figure 2, the brushes, polish, or other material are within easy reach. The rod 10 and legs 12 form a tripod or stand. The lug 21 acts as a lock to hold the stand open when in use and also serves to maintain the stand in locked position when closed.

I claim:

35 A shoeshine kit comprising an inclined rod having an eyelet on its upper end, a pair of spaced apart legs arranged in converging relation with respect to each other, said legs being spaced from the rod so as to form a tripod-like stand, a first section extending from the upper end of each of said legs and terminating in angularly arranged and parallel straight portions, a crosspiece interconnecting said straight portions together and said crosspiece projecting through said eyelet, a bracket secured to each of said legs, a hollow cover secured to said brackets and arranged contiguous to the inner surface of said legs, a container hingedly connected to the lower end of said cover for holding articles such as shoe polish, brushes, rags and the like, said first sections and straight portions coacting to provide a support for a person's foot when a shoe is being shined or polished, and an L-shaped lug for retaining said parts in open and closed positions, having one portion thereof secured to said container and with the other portion provided with a slot for slidably engaging said rod so as to maintain the parts in their closed position with sufficient friction to prevent accidental opening 45 thereof when said lug is moved into position adjacent the eyelet on the upper end of said rod, and whereby when the kit is in a folded position, the cover snugly closes said container, and when the kit is in open position, the lug forms a locking mechanism to hold the rod separated from the legs when said lug is moved into position adjacent the lower end of said rod, and when the kit is in open position the container is open and in a substantially horizontal position so that access can be readily had to the interior of the container as when the polish or brushes or the like are to be removed.
